UNITED STATES PATENT OFFICE.

FREDERICK W. HOCHSTETTER, OF NEW YORK, N. Y., ASSIGNOR TO PAUL M. PIERSON,
OF SCARBORO-ON-THE-HUDSON, NEW YORK.

RESTORATIVE FOR BLEMISHED MOVING-PICTURE FILMS.

1,139,681.

No Drawing.

Specification of Letters Patent. Application filed June 4, 1913. Serial No. 771,689.

Patented May 18, 1915.

To all whom it may concern:

Be it known that I, FREDERICK W. HOCHSTETTER, a subject of the Emperor of Germany, and a resident of New York, county 5 and State of New York, have invented a new and useful Restorative for Blemished Moving-Picture Films, of which the following is a full, clear, and exact specification.

This invention relates to a modified composition of matter disclosed in my pending applications for Letters Patent, Serial No. 732,465 filed November 20, 1912, and Serial No. 770,177, filed May 27, 1913.

The object of the invention is to provide certain ingredients designed to be utilized for treating moving picture films employed for exhibiting the motion acts of persons, or other objects upon a screen when the pictures thereof are impaired by scratches from 15 particles of dust, or when the film becomes hard and brittle during its transmission through a projecting apparatus, and which are adapted to restore the photography of the pictures by removing the blemishes thus 20 produced as well as restoring the flexibility of the film, thereby greatly adding to the durability and attractiveness of moving picture films.

My composition of matter consists of the following ingredients, combined in the proportions stated, viz:—vegetable, or mineral oil, such as oil of turpentine, benzin, naphtha, olive oil, cottonseed oil, oil of petroleum, oil of sweet almonds, linseed oil, sperm 35 oil, or the like by weight 6 ounces; spirits of camphor (U. S. P. strength) by weight 2 ounces; sulfuric ether (U. S. P. strength) by weight $\frac{1}{2}$ ounce; glycerin, by weight 1 ounce.

40 One or more of the oils, as occasion requires, are placed in a suitable vessel, and the spirits of camphor and glycerin are incorporated therewith by agitation through the employment of any desired method, or

the ingredients may be subjected to a gentle 45 heat if desired until the alcohol of the spirits of camphor is evaporated. After the mixture is cooled sufficiently, if heat is used, the sulfuric ether is then added and mingled with the other ingredients. 50

In practice this composition for restoring the pictures on films is used by applying a required quantity of the mixture upon the surface of the film through the medium of one, or more buffers made of chamois skin, 55 flannel, or other soft material. By then rubbing the coating on the film the mixture will penetrate the crevices of the scratches as well as soften the texture of the film for 60 restoring its flexibility. Upon the subsequent removal of all surplus of the mixture from the film with the use of a polishing cloth, or otherwise the scratches will be freed of the particles of dust, or other foreign substance, and the high lights and 65 shadows of the photography of the pictures will be restored to approximately their normal clearness.

Having thus described my invention, I claim as new and desire to secure by Letters Patent:—

1. The herein described restorative for moving picture films comprising in combination, an oil, spirits of camphor, sulfuric ether, and glycerin, substantially as set 75 forth.

2. The herein described restorative for moving picture films comprising an oil six ounces, spirits of camphor two ounces, sulfuric ether one-half ounce, and glycerin one 80 ounce, substantially as described.

This specification signed and witnessed this third day of June A. D. 1913.

FREDERICK W. HOCHSTETTER.
